SOLDERLESS CONNECTOR

Ralph H. Kingdon, Detroit, Mich., assignor to
 Square D Company, Detroit, Mich., a corpora-
 tion of Michigan

Application February 8, 1947, Serial No. 727,356

7 Claims. (Cl. 173—259)

1

This invention relates to a solderless connector for electric conductors in which electric cables are mechanically clamped in electrically conducting relation as distinguished from attachment by means of a solder lug.

An object of the invention is to provide a solderless connector which shall effectively, mechanically and electrically connect an electric cable to a conducting part with the connector receiving the cable end from the top of the connector rather than through an end opening.

Another object of the invention is the provision of a solderless connector in which a cable end may be inserted from the top in which the top or cover of the connector is hingedly mounted on the body portion thereof so as to pivot into a non-interfering position.

Another object of the invention is the provision of a solderless connector in accordance with the preceding object in which the swinging top or cover has means interlocking with the body portion of the connector to normally retain the cover in place.

Another object of the invention is the provision of a solderless connector in accordance with the two immediately preceding objects in which the cover and opposite sides of the connector are threaded to receive a clamping screw adapted to clamp the electrical conductors against the bottom of the connector.

Other objects and features of the invention will be readily apparent to those skilled in the art from the specification and appended drawing illustrating certain preferred embodiments in which:

Figure 1 is a top plan view showing a solderless connector according to the present invention.

Figure 2 is a side elevational view of the connector.

Figure 3 is a transverse sectional view on the line III—III of Figure 2.

Figure 4 is a longitudinal sectional view on the line IV—IV of Figure 3.

Figure 5 is an elevational view of the connector with the top cover swung into cable inserting position.

Figure 6 is a perspective view of one form of conducting strap with which the solderless connector may be associated.

The solderless connector, as shown in the drawings, is mounted upon an insulating base 1 and connects an electric circuit cable 2 to a conducting strap 3 which, as specifically shown, forms a terminal of a circuit interrupter and carries a contact 4 adjacent its inner end upon a pressed

2

out portion thereof. The connector comprises a main body portion 5, U-shaped in cross section as shown in Figure 3, within which the strap 3 is disposed. The body portion 5 is mounted on the base 1 by means of a stud 6 passing through a metallic insert 7 and an opening in the bight of the U-shaped body portion and threaded into the strap 3 as shown in Figures 3 and 4.

A separate top wall 8 for the connector has 10 depending side wall portions 9 and 11 embracing the side walls of the main body portion 5. At the back end of the connector, the depending wall portions 8 are individually hinged at 12 to the opposite side walls of the main body portion 5 15 so as to be swingably mounted thereon. Adjacent the front end, the depending side walls 9 and 11 are provided with inwardly extending projections 13 adapted to be received in openings or depressions 14 in the opposite side walls of the main 20 body portion 5 to normally hold the top 8 in assembled relation.

The opposite interior wall surfaces of the main body portion 5 are threaded at 15 and the top 8 has a central opening similarly threaded to receive a clamping screw 16 which is thus threaded 25 into the side walls of the body portion 5 and the opening in the top 8. The conducting strap 3 has its upper surface within the connector provided with a plurality of upwardly 30 extending projections 17 against which the strands of the cable 2 are pressed to prevent their withdrawal from the connector.

While the connector may be formed of any desired materials, it is preferred to form the main body portion 5 and the clamping screw 16 35 of a metal of relatively high conductivity since these parts serve to carry at least a portion of the current between the cable 2 to the conducting strap 3. While copper is acceptable for this purpose, in order to increase the strength of the connector, it has been found more desirable to 40 form these parts of bronze or brass.

The top is a non-current carrying part and as it serves structurally to prevent spreading apart 45 of the side walls of the main body portion 5 as well as receiving the screw 16, it is preferably formed of steel or similar material of high strength.

As shown in Figures 1 through 4, the end of 50 the cable 2 is clamped between the screw 16 and strap 3 to mechanically and electrically mount it in the connector. The screw 16 exerts its mechanical pressure not only through its engagement with the threads 15 in the opposite side 55 walls of the main body portion 5 of the connector,

but also through its threaded engagement in the steel top 8, with the top maintained on the main body portion of the connector by the hinges 12 and the interengaged projections and recesses 13 and 14. In mounting the cable 2 within the connector and particularly in the case of heavy cables which are relatively stiff and resist easy bending and forming operations, the screw 16 is either removed, or withdrawn until it engages only the threads in the top 8, whereupon the top is rotated or swung into the position of Figure 5 to uncover the connector. In this operation the projections 13 are disengaged from the openings or recesses 14 by the natural resiliency of the side walls of the top 8 and/or the side walls of the body portion 5. With the top 8 in the position of Figure 5, the cable end may be laid directly into the connector from the top in the position in which it is to be clamped. Thereafter, the top 8 is returned to its normal position paralleled to the bottom wall of the connector and the screw 16 is advanced inwardly into clamping relation with the cable end.

In the operative position of the screw 16 in which it is in threaded engagement not only with the top 8 but also with the side walls of the main body portion 5, the top is maintained in enclosed position not only by the interengagement of the projections and recesses 13 and 14 but also through the interconnection of the threaded portions of the top and main body portion by the screw itself.

While the connector has been illustrated with the strap 3 within its walls and serving to mount it in place, it is obvious that the connector may be mounted above the strap by the simple reversal of the positions of the end of the strap 3 and the bottom wall of the connector and, while certain preferred embodiments of the application have been specifically disclosed, it is understood that the invention is not limited thereto, as many variations will be readily apparent to those skilled in the art and the invention is to be given its broadest possible interpretation within the terms of the following claims.

What is claimed is:

1. In a solderless connector for electrically connecting an electric cable, a main body portion of substantially U-shape, a cap portion having depending side walls embracing the side walls of the body portion, means connecting the side walls of said body and cap portions to permit movement of the cap portion to uncover the connector from the top, an opening in said cap portion, and a clamping screw threaded in said opening and in the opposite side walls of the body portion and serving to clamp the end of an electric cable within the connector, said screw connecting the threads in said opening and those in the opposite side walls of the body portion so as to maintain the cap portion in clamping position on the body portion against the clamping force.

2. In a solderless connector for electrically connecting an electric cable, a main body portion of substantially U-shape formed of material of relatively high electrical conductivity, a cap portion formed of a material of relatively high mechanical strength and having depending side walls embracing the side walls of the body portion, means connecting the side walls of said body and cap portions to permit movement of the cap portion to uncover the connector from the top, an opening in said cap portion, and a

clamping screw threaded in said opening and in the opposite side walls of the body portion and serving to clamp the end of an electric cable within the connector, said screw connecting the threads in said opening and those in the opposite side walls of the body portion so as to maintain the cap portion in clamping position on the body portion against the clamping force.

3. In a solderless connector for electrically connecting an electric cable, a main body portion of substantially U-shape, a cap portion hingedly mounted on said body portion for swinging movement to uncover the connector from the top, interengaging means at said cap and body portion for normally maintaining the cap in its operative position connecting the opposite side walls of the body portion to prevent spreading thereof, an opening through said cap portion, and a clamping screw threaded in said opening and in the opposite side walls of said body portion for clamping the end of an electric cable within the connector, said screw connecting the threads in said opening and those in the opposite side walls of the body portion so as to maintain the cap portion in clamping position on the body portion against the clamping force.

4. In a solderless connector for electrically connecting an electric cable, a main body portion of substantially U-shape, a cap portion hingedly mounted on said main body portion for swinging movement to uncover the connector from the top, said cap portion having means engaging the opposite side walls of said body portion to prevent spreading thereof when the cap portion is in closed position, an opening through said cap portion, and a clamping screw threaded in said opening and in the opposite side walls of said body portion for clamping the end of an electric cable within the connector.

5. In a solderless connector for electrically connecting an electric cable, a main body portion of substantially U-shape, a cap portion having depending side walls embracing the side walls of the body portion, means hingedly connecting the side walls of the cap and body portions adjacent one end of the connector to permit swinging of the cap portion to uncover the connector from the top, interengaging means on the side walls of said cap and body portions adjacent the opposite end of the connector to normally maintain the cap portion in its operative position, an opening through said cap portion, and a clamping screw threaded in said opening and in the opposite side walls of said body portion for clamping the end of an electric cable within the connector.

6. In a solderless connector for electrically connecting an electric cable, a main body portion of substantially U-shape formed of a material having relatively high electric conductivity, a cap portion formed of a material having relatively high mechanical strength and having depending side walls embracing the side walls of the body portion, means hingedly connecting the side walls of the cap and body portions adjacent one end of the connector to permit swinging of the cap portion to uncover the connector from the top, an opening through said cap portion, and a clamping screw threaded in said opening and in the opposite side walls of said body portion for clamping the end of an electric cable within the connector.

7. In a solderless connector for electrically connecting an electric cable, a main body portion of substantially U-shape formed of material of

good electrical conductivity, a steel cap portion having depending side walls embracing the side walls of the body portion, means hingedly connecting the side walls of the cap and body portions adjacent one end of the connector to permit swinging of the cap portion to uncover the connector from the top, interengaging means on the side walls of said cap and body portions adjacent the end of the connector to normally maintain the cap portion in its operative position, an opening through said cap portion, and a clamping screw of good electrical conductivity threaded in said opening and in the opposite side walls of said body portion for clamping the end of an electric cable within the connector.
